UNITED STATES PATENT OFFICE.

LOUIS F. HESS, OF ANSTED, WEST VIRGINIA, ASSIGNOR TO HESS DUSTLESS MINING MACHINE COMPANY, OF ANSTED, WEST VIRGINIA.

MINING-TOOL.

1,059,463.

Specification of Letters Patent. Patented Apr. 22, 1913.

Application filed October 4, 1912. Serial No. 723,951.

To all whom it may concern:

Be it known that I, LOUIS F. HESS, a citizen of the United States, residing at Ansted, in the county of Fayette and State of West Virginia, have invented a new and useful Mining-Tool, of which the following is a specification.

The device herein disclosed is a cutter head for a mining machine, the cutter head 10 preferably being provided with a spiral rib.

In the rib are mounted a plurality of tool holders, tools being carried by the tool holders. In a device of this type, it is obviously desirable that the tool and the tool 15 holder shall not rotate upon an axis transverse to the axis of the cutter head, when the cutter head is rotated upon its own axis. There are no known mechanical means whereby a polygonal hole may be fashioned 20 practically in the cutter head, to the end that the tool holder and the tool may be prevented from rotating, as above mentioned, and the present invention aims, as one of its objects, to provide a means whereby a tool 25 holder may be mounted in a circular opening in the head, means being provided whereby the tool holder will be prevented from rotating in the circular opening, when the cutter head is rotated about its own axis.

Another object of the invention is to provide novel means whereby the tool which is 30 in the tool holder, may be braced and sustained while the cutter head is being rotated.

It is within the scope of the invention to 35 provide a cutter head and a tool holder, their construction being such that the tool holder may readily be removed without disturbing the other tool holders in the head.

With the above and other objects in view 40 which will appear as the description proceeds, the invention resides in the combination and arrangement of parts and in the details of construction hereinafter described and claimed, it being understood that 45 changes in the precise embodiment of invention herein disclosed can be made within the scope of what is claimed without departing from the spirit of the invention.

In the drawings: Figure 1 shows the invention in perspective; Fig. 2, is a longitudinal section of the tool holder, the tool being mounted therein; and Fig. 3 is a bottom plan of the tool holder, the tool being mounted therein.

In the accompanying drawings, the nu-

meral 1 indicates generally, the cutter head, the same being provided with a spiral rib 2. The convolutions of the rib are provided with transverse depressions 3, the depression 3 defining a primary shoulder 4, extended 60 transversely of the rib and longitudinally of the head 1. Extended circumferentially of the rib 2 is a slot 5, defining a secondary shoulder 6 and another secondary shoulder 7. The shoulder 7 is cut away as indicated 65 at 8, for a purpose which will be set forth hereinafter. The base of the slot 5 is denoted by the numeral 9. At the inner end of the base 9 of the slot 5, between the shoulders 6 and 7, within the contour of the 70 depression 3, and adjacent the primary shoulder 4, there is fashioned in the rib 2, a transverse opening 10 which is of circular contour. The opening 10 may be extended into the head 2 to any desired depth. 75

The invention further includes a tool holder denoted generally by the numeral 11 comprising a shank 12 and an arm 14 which extends at right angles to the shank 12. The shank 12 is of circular contour, as indicated 80 at 15, so as to register closely, and with a driving fit, in the opening 10. The shank 14 of the tool holder is of polygonal cross section. The shank 14 registers closely between the secondary shoulders 6 and 7, to 85 the end that the shank 12 may not rotate in the opening 10. The lower face of the arm 14 rests upon the base 9 of the slot 5.

The shank 12 of the tool holder is equipped with a socket 16 which is of polygonal cross 90 section. Mounted in the socket 16 and conforming closely thereto is a cutting tool 17, held in place by a set screw 18 which is threaded to the end of the arm 14. The tool 17 is provided with an overhanging portion 95 19, the cutting edge of which is indicated at 20. The overhanging portion 19 may rest upon the primary shoulder 4, the shoulder 4 constituting a support for the portion 19.

From the foregoing it will be seen that 100 when the cutter head 2 is rotated upon its own axis, the tool holder 11 and the tool 17 will be prevented from rotating upon an axis transverse to the axis of the cutter head 2, because the arm 14 of the tool holder is 105 engaged between the secondary shoulders 7 and 6, and particularly because one side of the arm 14 abuts against the shoulder 6.

In order to remove the tool holder 11 and the tool 17, as is necessary when the tool 110

needs sharpening, or when the set screw 18 becomes broken off, a wedge or drift is driven between the base 9 of the slot 5 and the lower face of the arm 14, the shank 12 of the tool holder being freed from the opening 10. Any one tool holder may, therefore, be removed readily from the cutter head 2, and it is not necessary to remove the cutter head from the machine and to carry the cutter head to the shop when a tool or two is replaced.

The construction of the device is such that the tool 17 may be elevated in the socket 12, and refaced as the tool is worn away, it being possible to utilize the tool until no more than three quarters of an inch of the shank 17 remains.

My co-pending application, Serial No. 730,480, filed upon the ninth day of November, 1912, discloses a cutter head for a mining machine, having some of the features shown in the mining tool constituting the subject matter of this application. In my co-pending application above referred to by serial number, a different invention from that herein claimed, is made the subject matter of the application; in that, in the co-pending application, Serial No. 730,480, the specific configuration of the rib is claimed, whereas, in this application, the specific means for holding the tool in place is claimed.

Having thus described the invention what is claimed as new is:—

35 1. A cutter head for a mining machine, provided with a circular, transverse opening; a tool holder including a circular shank fitting into the opening, the shank being provided with a polygonal, tool receiving socket; 40 and interengaging elements upon the tool holder and upon the head, for preventing the shank from rotating in the opening.

2. A cutter head for a mining machine, having a transverse shoulder, there being an

opening in the head at the inner end of the shoulder; and a tool holder comprising a shank disposed in the opening and an arm disposed at an angle to the shank, the arm abutting against the shoulder.

3. A cutter head for a mining machine, having a transverse slot defining spaced shoulders, there being an opening in the head at the inner ends of the shoulders; and a tool holder comprising a shank disposed in the opening and an arm engaged between the shoulders, the arm resting upon the base of the slot.

4. A cutter head for a mining machine, having a transverse slot defining spaced shoulders, there being an opening in the head between the inner ends of the shoulders; and a tool holder comprising a shank disposed in the opening and an arm engaged between the shoulders, the arm resting upon the base of the slot; one shoulder being cut away to permit the insertion of a lifting tool between the shank and the base of the slot.

5. A cutter head for a mining machine, having a spiral rib provided with a transverse depression defining a primary shoulder, there being a slot extended circumferentially of the rib and defining spaced secondary shoulders in the depression, there being an opening in the rib, between the secondary shoulders, and adjacent the primary shoulder; a tool holder including a shank disposed in the opening and an arm engaged between the shoulders; and a tool mounted in the tool holder, the tool comprising an angular portion for which the primary shoulder constitutes an abutment.

In testimony that I claim the foregoing as my own, I have hereto affixed my signature in the presence of two witnesses.

LOUIS F. HESS.
